United States Patent Office

Des. 217,515
Patented May 5, 1970

217,515

WIG HOLDER

Bertram B. Wells, Toronto, Ontario, Canada, assignor to
Bathurst Sales Limited, Toronto, Ontario, Canada, a
corporation of Ontario, Canada

Filed Mar. 13, 1969, Ser. No. 16,226

Term of patent 3½ years

Int. Cl. D20—02

U.S. Cl. D80—8

The figure is a front perspective view of a wig holder showing my new design, the rear being plain.

I claim:

The ornamental design for a wig holder, as shown and described.
